UNITED STATES PATENT OFFICE.

ARCHIE EDGAR LOW, OF OTTAWA, ONTARIO, CANADA.

MAIL-BAG LOCK.

Application filed January 22, 1927. Serial No. 162,771.

This invention relates to improvements in locks and more particularly to grommet locks provided with sealing as well as automatic locking means.

5 The objects of the invention are to provide a lock of this description of light and durable construction that will be practically proof against tampering.

10 A further object is to provide a combined locking and sealing member particularly adapted for securing mail bags and the like and having integral therewith a label holder.

15 With the foregoing and other objects in view, hereinafter more fully referred to, the essential features of my improved lock are

20 the combination with an automatic lock mechanism of a locking bolt adapted to engage with said mechanism and protruding therebeyond to carry a seal, a protecting plate for the lock mechanism and means operable from without the lock for unlocking the bolt.

25 Referring now to the drawings in which like characters of reference indicate corresponding parts in each figure.

Figure 1 is a perspective view of the improved lock.

30 Figure 2 is a plan view of the lock with the outside cover removed showing the baffle plate in place.

Figure 3 is a plan view with the cover and baffle plate removed showing the locking mechanism.

35 Figure 4 is a longitudinal section through the lock applied to a mail bag.

Figure 5 is a perspective view of the locking bolt showing the seal carrying means in the extended end thereof.

40 Figure 6 is a perspective detail of the unlocking key.

Figure 7 is a section on the line 7—7 Figure 1.

45 Referring more particularly to the drawings in which a preferred example of my improved lock is illustrated in connection with a mail bag, A designates the lock as a whole and B a mail bag creased at the top, as illustrated in Figure 4 in closed position.

50 The lock A comprises a metal base plate 10 of any suitable form, the lower end of which is bent upwardly at 11 to form in combination with the sides similarly bent as at 12 and 13, a slip label holder. Adjacent the top in the base plate 10 is a bolt opening 14 below which are pivotally mounted at 15 and 16, dogs 17 and 18 hooked at their upper

ends to substantially surround and register with the opening 14 in the plate. These dogs are spring actuated by means of spring members 19 and 20 consisting of strips of wire wound midway of their length on the pins 21 and 22 formed integral with the plate 10, the loose ends of these wires being normally retained in position by the cover 23 and contacting as at 24 with the dogs to exert pressure inwardly thereon whereby the dogs are automatically and normally spring actuated in closed, gripping position. The dog 17 is formed with a protruding bent lug 25 for purposes hereinafter more fully described.

Over the mechanism as above described is designed to securely fit a baffle plate 26 provided with a bolt opening 26^a to register with the bolt opening 14 in the plate 10. An opening 27 in the baffle plate is also provided to engage with the lug 25. A key opening 28 is further provided registering with a stem 29 on the plate 10 and which engages with a key 30. This key is formed with wards 31 and 32 and adapted when inserted to engage with the stem 29 and simultaneously when turned with the dog 18 and the lug 25 to operate the dogs 17 and 18 to release the bolt 33.

As illustrated in Figures 4 and 5, 33 is a locking bolt of any suitable length and adapted in the example of my invention here shown to extend through the pleated or creased top of a mail bag B and is provided at one end with a plate 34 of well known construction to which is connected in any well known manner the strap member 35 in turn rigidly connected at 36 to the mail bag. The bolt 33 extends through the opening 14 to be automatically gripped by the spring actuated dogs 17 and 18 through the groove 37 therebetween, this taking place with a click. Beyond this groove 37 the bolt is extended and tapered at the extremity as at 38 adjacent to which it is provided with an orifice 39 to engage with a seal 40, as illustrated in Figure 4.

It will thus be seen that the locking bolt 33 is designed to extend completely through the lock and to protrude beyond the lock cover 23 as at 41 to carry a seal thereby providing increased protection for the contents of a mail bag or the like, a safe-guard against tampering.

105 110 This seal means in combination with the baffle plate 26 within the lock casing are pro-

tective features of simple and durable construction that add materially to the effectiveness of the lock without increasing the cost of construction.

5 For securing the baffle plate 26 over the lock mechanism spaced orifices are formed adjacent the periphery adapted to engage with pins or the like 42 formed integral with the base plate 10 and registering with said 10 orifices providing means when clinched for securely retaining the plate in position on the mechanism. Besides the casing 23, as illustrated in Figure 1, through which, as already described, the seal carrying end of 15 the locking bolt 33 protrudes, is an orifice 43 in the cover 23 while the key opening 44 registers with the key opening 28 in the baffle plate permitting unlocking from without the lock. The cover 23 is retained in position 20 by the lugs 45 stamped integral therewith and designed to be riveted in the slots 46 in the base plate 10.

For retaining the locking bolt rigid and avoiding any chance of its being disengaged 25 when locked by lateral or other movement I provide flanges 37^a around the orifices 14 and 26^a in the base plate and baffle plate respectively.

30 In operation it will be found from the foregoing description the locking bolt, as disclosed in the present example of my invention, is passed through the top of the mail bag or the like and then into the opening 14 where it is automatically locked by engagement with the spring actuated locking dogs. The end of the bolt passes through the lock and extending therebeyond 35 and is sealed.

To unlock the device the seal has to be 40 broken, and the key inserted and turned, releasing the dogs from their automatic engagement with the bolt and permitting the latter to be withdrawn.

As many changes could be made in the

above construction and many apparently 45 widely different embodiments of my invention, within the scope of the claims, constructed without departing from the spirit or scope thereof, it is intended that all matter contained in the accompanying specification and drawings shall be interpreted as 50 illustrative and not in a limiting sense.

What I claim as my invention:—

1. In a mail bag lock, the combination with an apertured casing having spring actuated locking dogs pivotally mounted therein, of a locking bolt engaging with the casing apertures and protruding therebeyond, said bolt being formed adjacent the protruding end with a groove to automatically 60 engage with said dogs on the bolt being inserted through the casing, the protruding end of the bolt being cone-shaped and formed with an opening therein.

2. A mail bag lock comprising in combination, a housing having a key opening therein and a bolt opening therein, a base plate having a bolt opening therein, a pair of spring actuated pivotally mounted dogs on the base plate normally retained in a closed 70 position, a key engaging lug on one of said dogs, a superimposed baffle plate for the dogs rigidly secured to the base plate and provided with a bolt opening and a key opening, respectively, and a third opening for 75 engagement with said lug whereby on the lug being engaged by a key the dogs are automatically spread or opened to an unlocked position, a seal carrying locking bolt having a groove therein, and extending through the base plate and the housing to protrude beyond the housing and to be engaged in locking position by the locking dogs.

In witness whereof I have hereunto set 80 my hand.

ARCHIE EDGAR LOW.
